[57] CLAIM

The ornamental design for a combined sandbox and bench, as shown and described.

DESCRIPTION

FIG. 1 is a top and rear perspective view of a combined sandbox and bench showing our new design;
FIG. 2 is a top and front perspective view thereof;
FIG. 3 is a top plan view thereof;
FIG. 4 is a right side elevational view thereof; the left side elevational view being a mirror image thereof;
FIG. 5 is a front elevational view thereof;
FIG. 6 is a rear elevational view thereof; and,
FIG. 7 is a sectional elevational view thereof taken along line 7—7 of FIG. 3.
FIGS. 3-7 inclusive are shown in an enlarged scale for clarity of illustration.

FIG. 1

FIG. 2
